UNITED STATES PATENT OFFICE

151,938

DESIGN FOR A NECKLACE

Harry Reinstein, Rye, N. Y.

Application August 26, 1948, Serial No. 148,309

Term of patent 7 years

(Cl. D45—16)

To all whom it may concern:

Be it known that I, Harry Reinstein, a citizen of the United States, residing at Rye, in the county of Westchester and State of New York, have invented a new, original, and ornamental Design for a Necklace, of which the following is a specification, reference being had to the accompanying drawing, forming part thereof.

The chain links shown at the ends only of the chain extend all the way throughout the chain.

I claim:

The ornamental design for a necklace, as shown and described.

HARRY REINSTEIN.
